UNITED STATES PATENT OFFICE

GUSTAV E. JANSSON, OF WOLLASTON, MASSACHUSETTS, ASSIGNOR TO CONDIT ELECTRICAL MANUFACTURING CORPORATION, OF SOUTH BOSTON, MASSACHUSETTS, A CORPORATION OF MASSACHUSETTS

OIL-FILLED INSULATING BUSHING

Application filed June 30, 1926. Serial No. 119,723.

This invention relates to electric insulators and particularly to oil filled insulators of the bushing type which have an outer casing comprising a plurality of insulating sections.

Various methods have been proposed to prevent the escape of oil through the joint between the insulating sections. A cemented joint is desirable because of its simplicity and cheapness, but has the disadvantage that fluid, and especially oil, may, under certain conditions, slowly seep through the cement. Any loss of oil in a bushing of this type is attended by a corresponding weakening of the insulating properties of the bushing, hence a perfectly tight joint is a necessity. It is an object of this invention to provide a construction in conjunction with a cemented joint of an insulating bushing which will provide a fluid-tight joint thereat.

It is a further object to provide fluid sealing means for a cemented joint between two porcelain sections of a bushing of this type which can be readily inspected and repaired without dismantling the insulator.

A still further object is generally to improve the construction of oil filled insulating bushings.

Certain features herein illustrated and described are claimed in my co-pending application Serial No. 119,724 filed June 30, 1926.

Fig. 1 is an elevation partly in section of an insulator embodying the invention.

Fig. 2 is an enlarged sectional detail of the insulator of Fig. 1 in the vicinity of the attaching sleeve.

Fig. 3 is a plan view of the attaching sleeve.

As here shown, the insulating bushing embodying the invention comprises the upper insulating section 10 provided with the usual petticoats or capes 12, the lower insulating section 14 provided with external corrugations 16, and the intermediate metal attaching collar or sleeve 18 which surrounds the proximate ends of said sections 10 and 14. The upper insulating section comprises essentially a porcelain tube which is open at the top and bottom. The top of the insulator is provided with an oil reser-

voir consisting of a metal cylinder 20 which is secured in fluid tight relation to the open top of the upper insulating section 10. The oil reservoir is provided with a cover or cap 24 which is screw-threaded to the upper end of said cylinder 20 and forms a cover for the reservoir. A glass cylinder 26 is disposed within said cylinder 20 and the oil level in the insulator and in the glass cylinder 20 is visible at all times through suitable apertures 28 of the metal cylinder 20. Said reservoir cover 24 is provided with an axial opening through which a conductor or stud 32 is adapted to pass freely and said opening is covered against entrance of water by a cover 34 which is screw-threaded on said conductor and which has a depending apron 36 which surrounds said opening.

The lower insulating section 14 is provided with an opening in its lower end in which a bushing 38 is secured by means of a body of cement 40. Said conducting stud 32 is adapted to be screw-threaded through and extended beyond said bushing and a lock-nut 41 is screwed onto the lower extended end of said conductor to hold said stud against rotation. A packing 42 is disposed between said nut and the bottom of the insulator to provide an oil tight seal thereat.

Said metal collar 18 is provided with an integral outstanding flange 44 by which the bushing is adapted to be secured to the casting 46 of any suitable electrical apparatus. The internal diameter of said collar is adapted to be slightly larger than the diameter of the insulating sections 10 and 14 to provide an annular space therebetween to receive a body of cement 47 by which said upper and lower insulating sections are permanently and rigidly affixed to said attaching sleeve 18. Annular grooves 48 are provided on the inner surface of said sleeve into which the cement may enter, thus enhancing the strength of the joint. The inner edges of said sleeve 18 are bevelled at the top and bottom to provide the peripheral angular faces 50 which are preferably at an angle of about 45° with the side walls of the insulating sections 10 and 14.

As has been previously set forth, it has been

found that cement cannot be depended upon for a completely fluid tight joint under certain conditions on account of its porous structure and this is particularly true in the case of a fluid which has the penetrating qualities of oil. Consequently, means are provided to maintain an oil tight joint between the sleeve and the insulating sections 10 and 14 at the ends of the cement body. At the top of said sleeve said means preferably comprises an annular yielding packing 52, substantially triangular in section, which is adapted to encircle the upper insulating section, above the mass of cement 47 and to fit within the angular groove formed by said faces 50 and the insulating section 10. Said sleeve is provided with an outstanding annular flange 54 at its upper edge and bolts 55 passing through said flange are screw-threaded into a clamping ring 56 disposed above said flange and said packing. Said clamping ring is provided with an annular projection, or ridge, 58 which is arranged to bear against said packing 52 and to press it firmly against the angularly related faces of said sleeve and said insulating section 10, thereby providing a fluid-tight seal above the cement. A fluid tight joint is provided at the bottom of said sleeve 18 in a similar manner by the packing 60 and a clamping ring 62, which is secured to the sleeve by screw-threaded bolts 63.

This construction has the advantage that the fluid tight seal is not a part of the mechanical structure of the bushing and is readily accessible without dismantling the insulator in case it is desirable to renew the packing. The lower cape of said upper insulating section 10 may be provided with a metallic lining 65 in the vicinity of the metal sleeve 18 which lining is closely adherent to the surface and is conformed with the surface-irregularities of the bushing and said lining may be extended below said cape to a point where it will be connected electrically with the clamping ring 56 and consequently with the casing 46. The effect of this metal lining is to prevent a concentration of the flux at the top of the sleeve 18 and thus lessen the liability of breakdown at this point. The lining may be constructed of thin sheet metal as metal foil, or may be spray deposited or otherwise.

The construction may be modified without departing from the scope of the invention.

I claim:

1. An oil filled insulating bushing including an insulating conductor-enclosing shell, a metal supporting sleeve surrounding and connected with said shell, external sealing means for the joint between said sleeve and shell including a packing ring disposed at the end of said sleeve between it and said shell, a clamping ring carried by said sleeve arranged to bear against said packing ring,

and a thin metal coating mechanically independent of said sleeve carried by said shell at and extended above said sealing means arranged in strong mechanical adherence and in intimate contact with and conformed with the surface irregularities of said tube and having an electrical connection with said clamping ring.

2. An oil-filled insulating bushing including an outer oil-containing insulating shell comprising a pair of juxtaposed insulating tubes, a metal collar disposed about the confronting ends of said tubes and spaced from at least one of them, a body of cement in the space between said collar and tube, the oil within said shell having access to the cement, sealing means located in said space above the cement and arranged to seal the space against escape of oil passing through and around said body of cement, means including a metal clamping ring connected with said collar and bearing on said packing means, and an electrostatic shield carried by said insulating shell and located between it and said clamping ring, and connected electrically with said collar.

In testimony whereof, I have signed my name to this specification.

GUSTAV E. JANSSON.
